UNITED STATES PATENT OFFICE.

COULTER W. JONES AND ARTHUR E. SCHAEFER, OF MIDLAND, MICHIGAN, ASSIGNEES
TO THE DOW CHEMICAL COMPANY, OF MIDLAND, MICHIGAN, A CORPORATION OF
MICHIGAN.

METHOD OF MAKING HALOGENS.

1,036,121.

Specification of Letters Patent. Patented Aug. 20, 1912.

No Drawing.

Application filed September 23, 1909. Serial No. 519,244.

To all whom it may concern:

Be it known that we, COULTER W. JONES and ARTHUR E. SCHAEFER, citizens of the United States, and residents of Midland, 5 county of Midland, and State of Michigan, have jointly invented a new and useful Improvement in Methods of Making Halogens, of which the following is a specification, the principle of the invention being herein explained and the best mode in which we have contemplated applying that principle, so as to distinguish it from other inventions.

The present invention, relating, as indicated, to the making of halogens, has more 15 particular regard to the making of a halogen from a metallic haloid while simultaneously producing a haloid from the corresponding trioxygen salt. Stated more specifically, it is proposed to make chlorin, bromin or iodin 20 from a metallic chlorid, bromid, or iodid by treatment with a chlorate, bromate or iodate preferably of an alkali or alkaline earth, whereby the corresponding chlorid, bromid or iodid is simultaneously produced.

To the accomplishment of these and related ends, said invention, then, consists of the means and steps hereinafter fully described and particularly pointed out in the 25 claims.

The present improved process is based on the discovery that when certain metallic haloids are mixed with the tri-oxygen haloid salts of the alkalis or alkaline earths in water solution, the halogen of the metallic 30 haloid is liberated, the metal of the metallic haloid is oxidized and precipitated, and the tri-oxygen salt reduced to haloid. Thus, for instance, when potassium bromate and bromid of iron are brought together in a water 35 solution, bromin is liberated, ferric oxid precipitated, and potassium bromid formed. The reaction is quantitative, and by the use of the proper amounts of material practically all of the bromin in the bromid of iron 40 may be liberated, and recovered, the bromate

reduced to bromid, and the iron precipitated.

The following reactions indicate the chemistry of the process involved:

As indicated, these reactions take place without the addition of an acid to the reacting mixture.

It will, of course, be understood that the ferrous salts are first oxidized to ferric before the liberation of the bromin, and the reactions, as written, therefore express the net results.

In the following description, we set forth in detail one approved method of carrying out the invention, such disclosed mode, however, constituting but one of the various ways in which the principle of the invention may be used.

We prefer to mix together cautiously in a suitable closed vessel, practically chemical equivalent weights of bromid of iron liquor and bromate of potash, together with enough water to make a fluid pulp with the resulting precipitate. By applying heat, (most conveniently by the injection of steam) the bromin liberated by the reaction is driven off or distilled and may be condensed in suitable condensers or it may be used for the production of other bromids or in other processes. We have found that the reactions in question take place at room temperature slowly, even with dilute solutions. The rapidity of the reaction increases with the temperature. We find it most convenient to operate at the boiling temperature in order that the halogens liberated may be boiled off and at the same time the reaction accelerated. The bromid remaining in solution is then separated from the precipitate in any suitable manner, as by dilution, settling and decantation, or by filtration. If it be

desired to liberate also the bromin in this bromid, it may be conveniently done by the addition of more bromate together with an acid, such as sulfuric acid, by the well known reaction:—

and the liberated bromin may then be distilled off as before.

The original charge may conveniently contain enough bromate for both the reactions, the proper amount of metallic bromid liquor may then be added, and the acid after ward as required to complete the liberation of the remaining combined bromin. The solution should be dilute and the agitation active in order to confine the action of the acid, so far as possible, to the soluble bromid and bromate.

Other metallic bromids, such as bromids of nickel and cobalt, may be used in the same manner as above described for bromid of iron, and other bromates such as those of sodium may likewise be used. We write the following reactions:—

Metallic chlorids and iodids, as, for instance, chlorid or iodid of iron, may be used with a chlorate or iodate to produce chlorin or iodin and the corresponding chlorid or iodid. The following reactions will here apply:—

We are familiar with the well known use of chlorates with acid in the manufacture of bromin from bittern and mother liquors containing combined bromin, but we know of no instance of the use or application of reactions of the class above presented between metallic chlorids, bromids or iodids and chlorates, bromates or iodates for the liberation of the halogen in the metallic salt and for the simultaneous reduction of the chlorate, bromate or iodate without the use of acids. We are also familiar with the likewise well known method of distilling liberated bromin with heat or direct steam as described above and do not claim that as a part of our invention.

While iron is the specific metal, the haloid of which is herein referred to as being available for use in our improved method of making halogens, it will be understood of course that the remaining metals of the iron group will react in a similar fashion, and yet other metallic haloids may be found equally good for this purpose. Similarly,

while potassium bromate has been described as the preferred tri-oxygen haloid salt, it will be understood that in place of such potassium bromate the corresponding salts of other members of the alkali or alkaline earth groups of metals may be used. Wherever, accordingly, reference is made in this specification or the following claims to the tri-oxygen haloid salt of an alkali, it is intended to connote by the term "alkali," metals of the alkaline earth group as well.

Other modes of applying the principle of our invention may be employed instead of the one explained, change being made as regards the process herein disclosed, provided the steps stated by any one of the following claims or the equivalent of such stated step or steps be employed.

We therefore particularly point out and distinctly claim as our invention:—

1. In a method of making halogens, the step which consists in treating the haloid of a metal belonging to the iron group with a tri-oxygen haloid salt in a water solution and without the addition of an acid.

2. In a method of making halogens, the step which consists in treating the haloid of a metal belonging to the iron group with a tri-oxygen haloid salt of an alkali in a water solution and without the addition of an acid.

3. In a method of making halogens, the step which consists in treating an iron haloid with a tri-oxygen haloid salt in a water solution and without the addition of an acid.

4. In a method of making halogens, the step which consists in treating an iron haloid with the tri-oxygen haloid salt of an alkali in a water solution and without the addition of an acid.

5. The method of producing bromin, which consists in treating the bromid of a metal belonging to the iron group with a tri-oxygen haloid salt in a water solution and without the addition of an acid.

6. The method of producing bromin, which consists in treating the bromid of a metal belonging to the iron group with a tri-oxygen haloid salt of an alkali in a water solution and without the addition of an acid.

7. The method of producing bromin, which consists in treating the bromid of a metal belonging to the iron group with the bromate of an alkali in a water solution and without the addition of an acid.

8. The method of producing bromin, which consists in treating iron bromid with a tri-oxygen haloid salt in a water solution and without the addition of an acid.

9. The method of producing bromin, which consists in treating iron bromid with

the tri-oxygen haloid salt of an alkali in a water solution and without the addition of an acid.

10. The method of producing bromin,
5 which consists in treating iron bromid with a bromate in a water solution and without the addition of an acid.

11. The method of producing bromin,
10 which consists in treating iron bromid with the bromate of an alkali in a water solution and without the addition of an acid.

12. The method of making bromin, which consists in treating iron bromid with potassium bromate in a water solution and without the addition of an acid.

15

Signed by us this 18th day of September,
1909.

COULTER W. JONES.
ARTHUR E. SCHAEFER.
